SHEET FEEDING

Morris S. Gudger, New York, N. Y., and Frederick W. Seybold, Elizabeth, N. J., assignors to American Type Founders, Inc., Elizabeth, N. J., a corporation of New Jersey

Application June 29, 1939, Serial No. 281,989

16 Claims. (Cl. 271—27)

This invention relates to sheet feeding and more particularly to methods and apparatus for separating and forwarding sheets of metal or other stiff material to various types of processing machines, such as, for example, slitters, shears, punch presses, printing or lithographing presses, or the like.

The general object of the invention is to provide a novel and improved process and machine for efficiently separating sheets—more especially metal sheets—from a pile as received from the mill or from prior processing operations, and forwarding them in timed relation with the operation of the machine to which they are to be fed for further treatment.

Another object of the invention is to provide a machine of the class described which is generally automatic in operation, and equipped to relieve the operator of the necessity of performing a number of manual operations.

A further object is to provide a device of this description which is conveniently arranged, compact in construction, and which utilizes a minimum amount of floor space.

In its preferred embodiment, the invention contemplates the provision of a main supporting frame which houses most of the operating mechanism and serves also to support the pile carrying platforms from which the sheets are fed. Means are provided within the confines of the frame for successively separating the top sheets from the pile at their rear edges, lifting and moving them forwardly by engagement therewith at points adjacent their front edges, and finally transferring them to the machine. The efficient separation of the sheets is especially important in handling metallic sheets, such as tin plate or the like, due to the presence of oil or other adhesive materials which may have remained on the sheets after previous coating or processing operations, or due to rough or bent edges on the sheets themselves.

The separating and forwarding functions are performed by novel pneumatic gripping devices, comprising telescoping elements which are adapted to be extended and retracted by means of the same source of vacuum that is used to activate the suction cups on the lower ends of these devices. Novel timed valve mechanism is provided for actuating the grippers in the proper sequence to effect the separating and feeding processes.

The sheet feeder illustrated and described herein may also be provided with novel manually and automatically controlled pile elevating mechanism, and novel detector-caliper devices for pre-

venting the feeding of multiple sheets, or sheets of greater thickness than those for which the machine is set; and certain embodiments of these features form the subject matter of the copending applications, Serial No. 278,942, filed June 13, 1939, by M. S. Gudger, and Serial No. 281,990, filed June 29, 1939, jointly by M. S. Gudger and F. W. Seybold.

Other objects and features of novelty will be apparent from the following specification when read in connection with the accompanying drawings, in which one embodiment of my invention is illustrated by way of example.

In the drawings:

Figure 1 is a view in rear elevation of a machine embodying the principles of the invention; portions thereof being broken away and other portions being shown in vertical section for the sake of clearness of illustration;

Figure 2 is an enlarged view in vertical longitudinal section of the upper part of the device shown in Figure 1;

Figure 3 is a fragmentary vertical longitudinal sectional view of a portion of Figure 2, showing one of the forwarding elements in sheet delivering position;

Figure 4 is a view in vertical section of one of the suction grippers;

Figure 5 is a view in side elevation of the central plate of the rotary valve mechanism for controlling the actuation of the grippers;

Figure 6 is a transverse sectional view taken on line 6—6 of Figure 5; and also showing other portions of the valve assembly;

Figure 7 is a sectional view of the inner stationary valve plate taken on line 7—7 of Figure 5;

Figures 8 and 9 are elevational views of the two rotary valve bodies forming parts of the valve assembly illustrated in Figures 5 and 6; both figures representing the valve bodies as seen from the left in Figure 6.

Figures 10 to 13 inclusive are somewhat diagrammatic views in side elevation of the suction grippers showing them in the successive positions which they occupy during the feeding cycle; and

Figure 14 is a diagram on which are charted the relative positions and conditions of the suction grippers and their control valves, throughout the cycle of operation of the machine.

As most clearly shown in Figure 1 of the drawings, the novel sheet feeding machine comprises a supporting frame which includes the preferably unitary upper casting 10 and the four supporting legs 11 of substantially channel shape.

The feeding mechanism proper is conveniently disposed within the confines of the frame casting 10, and the piles of sheets are raised to a point within the range of operation of the feeders by 5 means of pile elevating mechanism which includes the cross frames 12 which support the platforms 14 upon which the sheets S are disposed. The transversely extending frames 12 are preferably arranged in pairs and are each provided with hooks 15 which are adapted to engage lugs 16 carried by the four sets of endless chains 18 which are guided around the sprockets 19 supported upon suitable bearing shafts, the lower ones 20 of which extend between adjacent legs 15 upon either side of the machine, and the upper ones 22 are provided with bearings in the frame casting 10. The upper chain shafts are provided intermediate their lengths with worm wheels 23 which are adapted to be driven by the worms 24 20 carried upon the elevator drive shaft 25 which may either be manually rotated by means of the wheel 26 or driven by the motor 27 through the gearing generally indicated by the reference numeral 30. Feeler mechanism for gauging the 25 height of the pile and controlling the pipe elevator is indicated generally at 31. These features will not be described in detail in the present specification since they form no essential part of the present invention, and are more fully disclosed in the copending application Serial No. 281,990.

The sheets from the pile S are forwarded to the feed roll 32 and its cooperating drop roll 33 from whence they are transferred by suitable 35 conveying means to the processing machine being fed. The separating of the top sheets T from the pile S and the forwarding of these sheets successively to the rolls 32 and 33 is accomplished by means of the front suction gripper members 35 and the rear suction gripper members 36. The rearwardly disposed grippers are not movable during operation of the feeder in a forward and rearward direction, but are confined to an approximately vertical movement for separating the top sheet from the remainder of the pile. These grippers are supported upon the transverse rod 38, each end of which is adjustably secured at selected points along the side bars 39 as by means of the clamps 40, the side 40 bars 39 being secured to the frame 10 as at 41. The rear suction separating grippers 36 are adjustably supported at selected points along the transverse rod 38 by means of the brackets 42. It will thus be seen that the rear grippers may 45 be positioned at desired points adjacent the side and rear edges of the piles of sheets of various dimensions.

During the separation, the rear corners of the top sheet are bent or curved upwardly and inwardly and also slightly upwardly and forwardly, in order to facilitate the separation of the top sheet from the underlying ones. For this purpose, the rear suction grippers 36 are pivotally adjustable with respect to the brackets 42 in a transverse plane about the pins 43 and the grippers may be tightened in adjusted positions appropriate to the size, thickness and material of the sheets, by means of the nuts 44. The brackets 42 are also adjustable angularly in a longitudinal plane about the transverse shaft 38 and may be clamped in the desired positions by means of the nuts 44'.

The forward suction gripper members 35 are mounted by means of the brackets 45 upon the 75 oscillating shaft 46. These brackets 45 may be

adjusted laterally of the machine along the shaft 46 in accordance with the width of sheets being fed. The shaft 46 is provided with two arms 47 and 48, each of which are provided with rollers 49 which contact respectively with the cams 50 and 51 carried upon the cam shaft 52. The cams 50 and 51 are so shaped that they will oscillate the shaft 46 to effect the swinging of the grippers 35 through a feeding cycle which will be described in detail hereinafter. 10

The operation of the feeding grippers and also of other parts of the machine, including the normal upward feed of the pile of sheets toward the grippers, may be effected in synchronism with the processing machine or other device to which 15 the sheets are ultimately fed. A shaft 55 is mounted in bearings at one side of the upper frame casting 10 and through the bevel gears 56 is made to drive the transverse shaft 57, this shaft having a sprocket 58 secured upon its outer 20 end. An endless chain 59 connects the sprocket 58 with a sprocket 60 on the shaft 61 of the feed roll 32. Another sprocket 62 on this same shaft is connected by means of the chain 63 with a sprocket 64 carried by the cam shaft 52. All 25 of this gearing is conveniently disposed upon the outside of the frame 10 and may be of course covered by a suitable guard for safety purposes.

Each of the suction gripper members comprises a cylinder 75 within which is adapted to 30 reciprocate a piston 76. The piston is hollow and is fitted around the tubular rod 77 upon the lower end of which is attached a suction cup element 78 as by means of the collar 79. The piston 76 is rigidly secured to the rod 77 between 35 the nut 80 and the shoulder 81. The rod 77 passes through the tubular boss 82 formed at the lower end of the cylinder. The upper end of the cylinder is closed by means of a screw cap or head 85, and communication with the upper and 40 lower ends of the cylinder upon either side of the piston 76 is obtained by means of the nipples 87 and 88 respectively. A coil spring 90 has its lower end secured as at 91 to the lower end of the rod 77 and its upper end is attached to the 45 pin 92 disposed centrally of the cap 85. It will thus be seen that the suction gripper members comprise a telescoping arrangement which is normally urged toward retracted position by means of the spring 90. The extension and retraction of the element at definite points during the cycle of operation of the feeder is accomplished by the introduction of varying pneumatic pressures into the cylinder upon the respective sides of the piston reciprocating therein. 55

For developing the pneumatic power for operating the grippers, there is provided the pump 95 which is connected by means of the sprocket gearing 96 to the transmission 30 driven by the electric motor 27. The vacuum pump 95 is connected with the vacuum tank 100 by means of the piping 101 and a flexible tube 102 connects this vacuum system with the rotary valve member 105 which is supported from the underside of the upper portion of the frame casting 10 as 60 at 106. Sections of flexible tubing 107 connect the casing of the valve assembly 105 with the rear suction grippers 36 and the tubing 108 connects the forward grippers 35 with the valve member. 70

Before the details of construction of the rotary valve 105 are set forth, it will be well to describe the cycles of operation of the forward and rear gripper members. In this connection, particular reference is made to Figures 2, 3, 4, 75

and 10 to 14, inclusive, of the drawings. For simplicity of illustration in these diagrams, the rear grippers 36 are shown in substantially vertical positions; but it is understood that in most cases the grippers will rise and descend along lines which are inclined to the vertical in both transverse and longitudinal directions. For purposes of comparison of the timing of the operation of the various elements, the diagram in Figure 14 has been prepared; the point at which the front or swinging grippers start their forward movement having been adopted as the zero point of the 360° cycles of movement shown upon the charts. From 0° to 120° the front grippers are being swung from their rearward position to their extreme forward position as shown in Figure 10 of the drawings. During this portion of the cycle the rear grippers 36 are idle, and from 0° to 110° the atmosphere ports of the lower chamber of the stationary grippers 36 are open. Between 110° and 120°, and while the top sheet T is still moving under control of the forward cylinders 35, but now out of range of the separating cylinders 36, the atmosphere port of the lower chambers of these latter grippers closes. Immediately following the closing of the atmosphere port the vacuum port opens, thereby effecting the lowering of the suction cup 78 of these grippers to the next underlying sheet of the pile, as indicated in broken lines in Figure 11 of the drawings. From 130° to 140°, and while the vacuum is effective in the lower chamber, the vacuum line to the upper chamber of the rear grippers opens while the atmosphere port is still closed (as indicated in chart IV), thus effecting the pneumatic seal of the suction head 78 against the sheet. By this time the previous sheet has passed between the feed rolls 32 and 33 and the forward grippers are dwelling at their forward limit of movement. At 140° the vacuum port for the lower chamber of the stationary grippers starts to close, and after it has closed at 150°, the atmosphere port opens gradually, as indicated by the curved portion *a* of the atmosphere valve line. The resulting unbalance of pressure above and below the piston retracts the gripper and moves the rear end of the sheet upwardly, slowly at first, and then more rapidly so that the acceleration is maintained at a point below that at which the suction seal with the sheet would be liable to break. During this lifting movement to the position shown in full lines in Figure 11, when the grippers 36 are inclined as in the preferred operation, the sheet is buckled somewhat as indicated by the dotted line *b* in Figure 1, this serving to more effectively separate the top sheet from the underlying ones. Suitable blast or winding devices may be provided for blowing air beneath the top sheet to aid in the separation and forwarding operations.

When the sheet is seized between the drop rolls 33 and the feed rolls 32, the atmosphere port of the upper chamber of the forward moving grippers opens, as shown at 130° in chart II, releasing the sheet from the suckers. The moving grippers remain in their forward position from 120° to 160° due to the appropriate shaping of the cams 50 and 51 which control the swinging of these members. These grippers move rearwardly from 160° to 280°, and during most of this time the rear end of the sheet has been held by the vacuum existing in the upper chamber of the stationary grippers. At 300° the atmosphere port of the lower chamber of the moving grippers closes and the vacuum port opens,

as shown in chart III, causing the piston to move downwardly until the suction cup contacts the forward portion of the top sheet T, as shown in dotted lines in Figure 13 of the drawings. At this time the vacuum port opens to the top chamber and then at 340° the atmosphere port of the lower chamber opens and the forward grippers retract and lift the forward end of the sheet as shown in Figure 13. Then at 320° the atmosphere port of the upper chamber of the rear separating grippers 36 opens (see chart IV) and the rear end of the sheet is released. This occurs between the positions illustrated in Figures 13 and 10 of the drawings. From 340° to 360° the front end of the sheet is rising to the position shown in Figure 13, ready to be forwarded to the feed rollers as in Figure 10.

The rotary valve member 106 is illustrated in detail in Figures 5 to 9, inclusive, of the drawings and comprises the stationary central plate 20 110 to which the end casing plates 111 and 112 are secured adjacent their margins. Bearing sleeves 113 are provided centrally of these plates for the valve operating shaft 115. The bearing opening at one end of the valve assembly is sealed by the cover 116 which is secured by means of the bolts 117. The shaft is packed at the other end of the valve housing as by means of the annular plate or gland 118 secured by means of the bolts 119. The shaft passes freely through the central opening 120 in the plate 110 and the space 120 is placed in communication with the supply of lubricant by means of the tube 121 and the bore 122. Keyed to the shaft 115 as at 123 and 124 are the rotary valve elements 125 and 126 which fit snugly against the opposite faces of the central plate 110 for rotation with respect thereto. The valve actuating shaft 115 is supported at its end remote from the valve casting in the bracket 128 and carries upon its outer end a sprocket 129 which is driven by means of the chain 130 from the sprocket 131 on the end of the cam shaft 52.

The stationary plate 110 of the valve assembly is provided with annular grooves 135 and 136 in its opposite faces and both of these grooves are connected by the transverse bore 138 with the radial passageway 139 which leads into the hollow internally threaded boss 140 which is adapted to be connected by means of the tube 182 with the vacuum tank 100. By this means both of the grooves or channels 135 and 136 are in continuous communication with the source of vacuum. A radial passageway 142 provides communication between the short transverse passageway 143 which opens into the left-hand face of the plate 110, as viewed in Figure 6, and the internally threaded boss 145 which communicates through one of the tubes 108 with the upper chambers of the forward gripper cylinders. The lower end of the chambers of the front cylinders are connected to the hollow boss 147, which is in communication with the opening 148 in the same face of the plate 110 but further from the center thereof than the opening 143. The lower chambers of the rear gripper cylinders are similarly connected through the hollow threaded boss 149 with the opening 150 in the left-hand face of the plate 110 outwardly of the groove 135. The upper ends of the rear cylinders are placed in communication through certain of the tubes 107 with the boss 152 which is connected by means of the radial passageway 153 with the short transverse passage 154 which opens upon the left-hand face of the plate 110, as viewed in 75

Figure 6, at a point inwardly of the groove 135, and at the same distance from the center as the opening 143 in the opposite face of the plate.

In Figure 8 of the drawings, there is illustrated the rotary valve member 126 as seen from the left in Figure 6. This member is arranged to rotate in the direction of the arrow and during this rotation the vacuum cavity 160 which has a relatively narrow portion 161 which continually overlies the vacuum groove 136, and a wider extension 162 which is intermittently brought into registry with the opening 143 leading to the upper end of the front cylinders. The cavity portion 162 has a shallower extension 163 for the purpose of somewhat restricting the vacuum during a certain portion of the time. Another vacuum cavity 165 is provided in the rotary member 126 and this cavity has a narrow portion 166 continually in communication with the groove 136 and a somewhat wider portion 167 which is regularly brought into communication with the opening 148 as clearly shown in Figure 6 of the drawings. It will be noted that the rotary valve disc or plate 126 is of a generally smaller diameter than the interior chamber of the valve and is provided with an extension 170 which tapers off at one side as at 171 to finally merge with the main circular periphery of the plate. This extension is adapted to cover the opening 148 leading to the lower end of the front cylinders at certain times to prevent communication with the atmosphere, with which the interiors of the chambers are continually in communication by means of the openings 173 and 174 in the respective cover plates 111 and 112. When these openings 148 are not covered by the extensions 170 of the member 126, the lower ends of the front cylinders are in communication with the atmosphere, or may be subjected to a slight super-atmospheric pressure in certain cases. The tapered portion 171 of the extension 170 provides for a gradual admission of atmospheric pressure to these connections. An opening 175 is drilled through the plate 176 in order to admit atmospheric pressure to the opening 143 leading to the upper end of the front cylinders at the proper point during the cycle.

The rotary valve plate 125 shown in Figure 9 of the drawings is adapted to move in the direction of the arrow and is illustrated in this figure as seen from the left in Figure 6. This plate is provided with a vacuum cavity 177 having a smaller extension 178 in communication with the vacuum groove 135 and a longer extension 180 which is adapted to register with the opening 154 leading to the upper end of the rear gripper cylinders during the designated portion of the cycle. The cavity 182 has its smaller end 183 continually in communication with the vacuum groove 185 and the widened portion 184 adapted to register with the opening 150 leading to the lower end of the rear gripper cylinders at the proper times. This plate is similarly provided with an extension 186 having a tapered portion 188 for the control of the communication of the lower end of the rear cylinders with the atmosphere. An opening 188 is also provided for admitting atmospheric pressure at the proper time to the opening 154 of the upper end of the rear cylinders.

It will thus be seen that these rotary valve members are so designed that the respective vacuum and atmospheric pressure cavities and openings are in registry with the corresponding ducts communicating with the upper and

lower ends of the suction gripper cylinders as to cause them to follow the sequence of operation already described in connection with Figures 10 to 14 of the drawings.

The vacuum in the tank 100 may be broken at any time by means of the manual valve 190 which normally covers the openings 191 in the cover member 192. The valve has a stem 193 which extends through the member 192 and is spring connected with the hand lever 194 pivoted to the bracket 195. The hand lever is moved to the right against the pressure of the spring 196 to open the valve.

It is understood that various changes and alterations may be made in the embodiments illustrated and described herein without departing from the scope of the invention as defined in the following claims.

Having thus described the invention, what is claimed as new and desired to be secured by Letters Patent is:

1. In a sheet feeder of the class described, a suction gripper comprising, in combination, a cylinder, a piston adapted to reciprocate within said cylinder, said piston dividing the interior of said cylinder into upper and lower chambers, a rod secured to and extending from the piston through one end of said cylinder, a suction cup on the outer end of said rod, said rod and piston being provided with a bore communicating with the upper cylinder chamber, and separate means for individually placing the upper and lower chambers of said cylinder in communication with sources of vacuum and pressure, the evacuating of the upper chamber serving both to effect the gripping of the sheet and then the lifting of the rod and attached sheet when the cup is sealed.

2. In a sheet feeder of the class described, a suction gripper comprising, in combination, a cylinder, a piston adapted to reciprocate within said cylinder, said piston dividing the interior of said cylinder into upper and lower chambers, a rod secured to and extending from the piston through one end of said cylinder, a suction cup on the outer end of said rod, said rod and piston being provided with a bore communicating with the upper cylinder chamber, and openings communicating respectively with the upper and lower chambers of said cylinder, a source of vacuum, conduits connecting said source of vacuum with said openings, valve means disposed in said conduits for individually controlling the communication of said openings with said source of vacuum, and means for intermittently actuating said valve means during the operation of the feeder.

3. In a sheet feeder of the class described, a suction gripper comprising, in combination, a cylinder, a piston adapted to reciprocate within said cylinder, said piston dividing the interior of said cylinder into upper and lower chambers, a rod secured to and extending from the piston through one end of said cylinder, a suction cup on the outer end of said rod, said rod and piston being provided with a bore communicating with the upper cylinder chamber, and openings in said upper and lower chambers of the cylinder for communication with sources of fluid pressure or vacuum, a tension spring connecting the upper end of said cylinder with the reciprocating piston and rod assembly and tending to urge the latter upwardly within the cylinder.

4. In a sheet feeder of the class described, a

5 suction gripper comprising, in combination, a cylinder, a piston adapted to reciprocate within said cylinder, said piston dividing the interior of said cylinder into upper and lower chambers, a
 10 rod secured to and extending from the piston through one end of said cylinder, a suction cup on the outer end of said rod, said rod and piston being provided with a bore communicating with the upper cylinder chamber, and openings in said
 15 upper and lower chambers of the cylinder for communication with sources of fluid pressure or vacuum, a tension coil spring connected at its upper end with the upper head of said cylinder, extending through said bore and secured at its lower end to the rod at a point adjacent said suction cup.

6. In a sheet feeder of the class described, a suction gripper comprising, in combination, a cylinder, a piston adapted to reciprocate within
 20 said cylinder, said piston dividing the interior of said cylinder into upper and lower chambers, a rod secured to and extending from the piston through one end of said cylinder, a suction cup on the outer end of said rod, said rod and piston being provided with a bore communicating with the upper cylinder chamber, a tension coil spring connected at its upper end with the upper head of the cylinder, extending through said bore and secured at its lower end to the rod at
 25 a point adjacent said suction cup, and separate means for individually placing the openings in the upper and lower chambers of said cylinder in communication with sources of vacuum and pressure.

30 7. In a sheet feeder of the class described, in combination, pivoted suction grippers for seizing the forward portion of a sheet, lifting and forwarding the sheet from a pile, a source of vacuum, a rotary multiple valve assembly for intermittently placing said grippers in communication with said source of vacuum, a rotary shaft upon which the rotary valve member is secured, a cam shaft, a cam on said shaft for oscillating said suction grippers, a sprocket chain between
 35 said cam shaft and said valve shaft, whereby said valve is operated in synchronism with the operation of said grippers, additional grippers for seizing and lifting the rear portions of said sheets, and means for placing said last named
 40 grippers in communication with said valve for synchronous operation.

45 8. In a sheet feeding device of the class described, a rotary valve assembly for controlling the intermittent communication of fluid pressure to the suction grippers, said assembly comprising a central substantially cylindrical plate, a pair of hollow casings secured to each lateral face of each plate to provide valve chambers adjacent thereto, an annular groove formed in
 50 each face of said plate, radial passageways in said plate, certain of said passageways communicating with said grooves and others opening through the faces of said plate at points spaced from said grooves, valve plates disposed within
 55 said chamber for rotation in contact with said lateral faces, a shaft upon which said valve plates are secured, means for rotating said shaft, said valve plates being provided with recesses adapted to place certain of said openings in said central
 60 plate in communication with said respective grooves, and means formed on said plates for gradually placing certain of said openings in communication with said chambers.

65 9. A sheet feeding device of the class described comprising a front suction gripper and a rear

70 suction gripper adapted to perform sequential separating and feeding operations upon successive sheets of a pile, each of the grippers comprising a cylinder, a piston adapted to reciprocate therein and to divide said cylinder into upper and lower chambers, a rod connected to said piston and extending through one end of said cylinder and having a suction cup secured to the projecting end thereof, a source of vacuum, a rotary valve assembly for controlling the intermittent communication of vacuum and atmospheric air to the respective chambers of the suction grippers, said valve assembly comprising a central substantially cylindrical plate, a pair of casings secured to each lateral face of said plate to provide valve chambers adjacent thereto, an annular groove in each of said faces, a radial passageway in said central plate communicating with said source of vacuum and with both of said grooves, other radial passageways in said central plate communicating respectively with the upper and lower ends of said front and rear suction gripper cylinders, the passageways which communicate with the forward grippers opening at radially spaced points on one of said lateral faces and the passageways which communicate with said rear grippers opening at radially spaced points on the other of said faces, rotary valve plates disposed within said valve chambers for rotation in contact with the respective lateral faces of said central plate, said valve plates being provided with recesses adapted to intermittently and sequentially place said openings in communication with said grooves, whereby the upper and lower chambers of said forward and rear grippers are placed in communication with the source of vacuum in the proper sequence to effect the intermittent extension and retraction of said gripper elements.

75 10. A sheet feeding device of the class described comprising a front suction gripper and a rear suction gripper adapted to perform sequential separating and feeding operations upon successive sheets of a pile, each of the grippers comprising a cylinder, a piston adapted to reciprocate therein and to divide said cylinder into upper and lower chambers, a rod connected to said piston and extending through one end of said cylinder and having a suction cup secured to the projecting end thereof, a source of vacuum, a rotary valve assembly for controlling the intermittent communication of vacuum and atmospheric air to the respective chambers of the suction grippers, said valve assembly comprising a central substantially cylindrical plate, a pair of casings secured to each lateral face of said plate to provide valve chambers adjacent thereto, an annular groove in each of said faces, a radial passageway in said central plate communicating with said source of vacuum and with both of said grooves, other radial passageways in said central plate communicating respectively with the upper and lower ends of said front and rear suction gripper cylinders, the passageways which communicate with the forward grippers opening at radially spaced points on one of said lateral faces and the passageways which communicate with said rear grippers opening at radially spaced points on the other of said faces, rotary valve plates disposed within said valve chambers for rotation in contact with the respective lateral faces of said central plate, said valve plates being provided with recesses adapted to intermittently and sequentially place said openings in communication with said grooves, whereby the upper and lower chambers of said forward and rear grippers are placed in communication with the source of vacuum in the proper sequence to effect the intermittent extension and retraction of said gripper elements.

MORRIS S. GUDGER.
FREDERICK W. SEYBOLD.
